UNITED STATES PATENT OFFICE.

WILLIAM HUGERSHOFF, OF NEW YORK, N. Y.

TURNING-LATHE.

No. 800,304.

Specification of Letters Patent.

Patented Sept. 26, 1905.

Application filed October 5, 1904. Serial No. 227,269.

To all whom it may concern:

Be it known that I, WILLIAM HUGERSHOFF, a citizen of the United States, residing in New York, borough of Bronx, in the State of New York, have invented certain new and useful Improvements in Turning-Lathes, of which the following is a specification.

This invention relates to improvements in lathes for turning forms.

10 It relates more especially to lathes employed for turning regular or irregular forms from india-rubber or other light refractory material.

The invention consists in certain combinations of parts and in certain details of construction, all of which will be fully described hereinafter and finally pointed out in the claims.

15 In the accompanying drawings, Figure 1 represents a side elevation of a lathe embodying my invention. Fig. 2 is a top view of the same. Fig. 3 is a vertical transverse section on line 3-3, Fig. 2, looking in the direction of the arrow shown in said figure. Fig. 4 is a vertical longitudinal section through a portion of the lathe on line 4-4, Fig. 2; and Fig. 5 is a detail plan view, partly in horizontal section, of a portion of the tool-head.

20 Similar letters of reference indicate corresponding parts.

Referring to the drawings, A indicates the bed of the lathe, which can be of any suitable form. Upon the bed is mounted a head-stock B and a tail-stock C, said tail-stock being preferably adjustable in the usual manner. A standard D is also mounted on the bed A between the head-stock and the tail-stock and serves to guide the spindle of the latter, as will be presently described. The 25 tail-stock is provided with a spindle a, longitudinally adjustable in the usual manner by means of a hand-wheel a'. The work E is centered between the spindle a and the chuck a'', which may be of any suitable form, and is secured to the spindle a' of the head-stock. At diametrically opposite sides of the work is arranged a frame F, guided in standards a⁴ a⁵ a⁶ a⁷, so as to be capable of reciprocation longitudinally in said standards 30 parallel with the axial line of the work between the spindle and the head of the tail-stock. The standards a⁴ a⁵ a⁶ a⁷ are adjustable longitudinally and transversely of the bed A of the lathe by means of suitable 35 clamps a⁸ a⁹. At its end toward the tail-stock the frame F is connected with a feed-

screw b. Said screw is mounted loosely upon spindle a, as indicated in Fig. 4, and is provided, as also indicated in Fig. 4, with tight and loose pulleys b' b'' f' f'', respectively, over 40 which passes a power-belt b³ and a cross power-belt e² from any suitable source of power—as, for instance, a power-shaft e³, elongated so as to connect the belts at any point between the standard D and the tail-stock C. The feed-screw b is threaded in the standard D and is connected at its forward end beyond said standard with the rear transverse portion or cross-head b⁴ of the frame by means of a pin or stud b⁵ entering a groove 45 b⁶ in the feed-screw b. The feed-screw is thereby connected to the frame in such a manner as to permit rotation independently of the same, but so as to move longitudinally therewith and by its rotation under the action 50 of the belt b³ to feed or screw forward through the standard D, and thereby advance the frame F along the work.

The frame F carries tool-holders, preferably two in number, each comprising a rod c 55 guided in the bushing c' of the frame F and extending forwardly toward the axial line between the centers of the machine and then arched, as indicated at c², over the normal position of the work to the rear rod c³ of the 60 frame, upon which it is guided by means of a yoke or eye c⁴, and provided at its rear extremity with an antifriction-roller c⁵, adapted to bear upon a form or model c⁶ of the work to be produced, which is mounted in any suitable 65 manner at the rear part of the machine—as, for instance, between the centers c⁷ c⁸. At a point approximately at the junction of the arched portion c² with the rod c is formed a tool-head c⁹, to which the cutting-tools d', 70 preferably two in number, are each secured at opposite sides by means of slot-screws, as indicated in Fig. 5. Between each tool-head and each bushing c' is arranged a compression-spring d², by means of which the tool-support 75 is actuated normally in forward direction toward and against the work. The bushings c' are threaded in the frame F, as indicated, and thereby enable the adjustment of the springs so as to produce greater or lesser pressure of 80 the tools upon the work, as may be desired, and thereby adjust the tools to the best advantage according to the hardness of the material to be cut and the particular kind of tools used.

85 In order to support the tools more firmly and secure a more reliable and effective cut-

ting of the work, a tool-rest d^3 is arranged upon the bed of the lathe, as indicated, said tool-rest being so arranged as to support the tools in their travel along the work. As before stated, two sets of tools are preferably employed. This construction is provided for the reason that india-rubber when vulcanized is a material of some difficulty to work, and in order to avoid chipping and to produce smooth cuts and smooth surfaces it is preferable to pass a number of tools over the surface, each making a small cut, than to pass a single tool once over the surface with a deeper cut. The frame F is shown in the drawings in approximately horizontal position. It may, however, by means of the standards a^4 a^5 a^6 a^7 be adjusted at either side, either higher or lower than shown, in such manner as to adjust the tools and place the same either above or below the center, as desired, for the better cutting of the work or for bringing the entire frame into an inclined or tilted position in case such position should be desirable. The adjustment is accomplished by mounting the supporting-rods e of the standards in hollow posts e', in which they are secured by means of set-screws, as shown. The work is rotated by means of a power-belt applied to the cone of the head-stock in the usual manner.

For turning by means of my improved lathe—for example, a telephone-receiver, for which operation the lathe is specially desired—a finished form is placed between the centers c^7 c^9 and the stock to be cut placed in the chuck and supported at its outer end by the tail-stock center a. The power-belt b^3 is now moved upon the tight pulley b' and the cross-belt e^2 moved upon the loose pulley f^2 . The feed-screw is thereby rotated and screws forward through the standard D, advances the frame F, and carries the tools thereby toward the head-stock along the work, each tool cutting the same successively deeper than the preceding until the tools arrive at the limit of motion, when the belt b^3 is shifted back onto the loose pulley b^2 . Both belts are now on loose pulleys. During the advance movement of the frame with the tools the antifriction-rollers have traversed the form c^6 and have thereby guided the tool-supports in a path corresponding to the form, so that the work has been cut in exact correspondence therewith. The work is now removed in the usual manner by withdrawing the spindle a and releasing the work from the chuck and another unfinished piece of stock is placed in position in the chuck and the tail-center fixed. The cross-belt e^2 is now shifted to the tight pulley f' , whereby the feed-screw is caused to rotate in a direction opposite to its motion first described, thereby screwing in backward direction through the standard D and drawing back the frame F, and with the same the tools, along the new piece of stock. The tool-sup-

ports follow the form c^6 in the manner before described, and the tools cut successively into the work during the traverse of the same, so that when the frame is entirely withdrawn into its original position the work is completed.

70

The belt e^2 is then shifted onto the loose pulley f^2 , whereby the frame is brought to rest and the finished work may be removed and a new piece inserted in the same manner as before.

75

It will be understood that many modifications in the details of the construction may be made without departing from the spirit of the invention. For example, in place of a chuck a mandrel may be used for the support of the work, and such mandrel is customarily used, although for purposes of illustration a chuck has been shown in the drawings. Any other means of support may be provided.

Having thus described my invention, I claim as new and desire to secure by Letters Patent—

1. In a turning-lathe, the combination, with means for supporting and rotating the work, a form, and a longitudinally-reciprocating frame guided at each side of the work, of a tool-support carried by said frame and comprising a rod guided at each end in said frame, said rod being provided with an intermediate arched portion and bearing at one end against said form, a tool-head at the junction of said arched portion with the main portion of said rod, and a tool carried by said tool-head.

95

2. In a turning-lathe, in combination, a bed, means thereon for supporting and rotating the work, a form, a plurality of upright standards arranged at either side of said bed, a longitudinally-reciprocating frame embodying longitudinally-extending rods guided in said standards, a tool-support guided transversely of said frame and bearing against said form, and a tool carried by said support.

100

3. In a turning-lathe, in combination, a bed, means thereon for supporting and rotating the work, a form, a plurality of upright standards arranged at either side of said bed and adjustable longitudinally and transversely thereof, a longitudinally-reciprocating frame embodying rods guided in said standards, a tool-support guided transversely of said frame and bearing against said form, and a tool carried by said support.

115

4. In a lathe, in combination, a bed, means for supporting and rotating the work, a form arranged in proximity to the latter, a longitudinally-reciprocating frame guided at each side of the work, a tool-support carried by said frame and bearing against said form, a tool carried by said support, and a fixed tool-rest arranged on said bed for supporting said tool throughout the longitudinal cutting movement thereof.

120

5. In a lathe, in combination, a head-stock, means for rotating the work, a tail-stock provided with a centering-spindle, a standard between said head-stock and said tail-stock for

130

guiding said spindle, a tubular feed-screw inclosing said spindle and extending between said tail-stock and said standard, a frame guided longitudinally of the work and attached 5 to said feed-screw so as to move longitudinally therewith but rotate independently thereof, a tool-support carried by said frame, and a tool carried by said support.

6. The combination, of means for supporting and rotating the work, a form, a frame guided longitudinally at each side of the work, means for longitudinally reciprocating the frame, a tail-stock provided with a center spindle, a feed-screw connected with said 10 frame, so as to move longitudinally therewith

but rotate independently thereof, a standard receiving said feed-screw, said tail-stock spindle extending through said feed-screw to the work, tight and loose pulleys on said feed-screw, a tool-support carried by said frame 20 and adapted to bear against said form, and a tool carried by said support.

In testimony that I claim the foregoing as my invention I have signed my name in presence of two subscribing witnesses.

WILLIAM HUGERSHOFF.
